UNITED STATES PATENT OFFICE.

DAVID W. JONES AND WILLIAM J. MILLER, OF COLUMBUS, OHIO, ASSIGNEES OF ONE-
THIRD TO JULIUS F. STONE, OF COLUMBUS, OHIO.

EXPLOSIVE-ENGINE.

1,081,120.

Specification of Letters Patent.

Patented Dec. 9, 1918.

Application filed March 31, 1916. Serial No. 552,602.

To all whom it may concern:

Be it known that we, DAVID W. JONES and WILLIAM J. MILLER, citizens of the United States, residing at Columbus, in the county of Franklin and State of Ohio, have invented a certain new and useful Improvement in Explosive-Engines, of which the following is a specification.

One object of this invention is to secure 10 a noiseless and efficient valve mechanism for a four cycle type internal combustion motor.

A further object is to provide a construction that promotes the cooling of the parts.

The invention consists in the constructions 15 and combinations of parts set forth in the claims.

In the accompanying drawings showing 20 an embodiment of the invention—Figure 1 is a vertical section on the line $\alpha-\alpha$ Fig. 2 looking toward the gearing side. Fig. 2 is 25 a horizontal section on the line $y-y$ Fig. 1, looking down.

In the views 3 designates the work or 30 explosion cylinder, 4 the intake-valve chest, and 5 the exhaust-valve chest. The said 35 chests are shown as cylindrical, open at the top and as located at opposite sides of the cylinder and parallel thereto. The work cylinder is provided with an intake port 6, main exhaust port 7 and auxiliary exhaust port 8.

The character 9 designates the intake-valve which is generally of the reciprocating 35 piston or sliding variety and fits in the chest thereof. We make this valve hollow but with a tubular conductor or passage 9^a extending across and through but not transversely closing the chest. The intake 40 chest is provided with an intake port 4^a and a ventilating opening 4^b in the outer wall of the chest. The lower end of the valve 9 is closed with septum 4^c just above which is a ventilating opening 9^b.

The character 10 designates the exhaust 45 valve which generally is of the reciprocating piston or sliding variety and fits in the chest 5 therefor. We also make this valve hollow but with a tubular conductor or passage 10^a intersecting its interior and extending through it. In this instance the 50 walls forming the tube 10^a close the lower end of the valve, and ventilation is secured by means of a vent 10^b, above the passage 10^a in the valve and a vent 5^b in the outer 55 wall of the chest 5. The port 10^c consti-

tutes the main exhaust port of the exhaust valve, said port working over the corresponding exhaust port 7 of the cylinder. The tube 10^a which works over the auxiliary exhaust port of the cylinder constitutes the 60 passage through the valve for the discharge of burnt gas from the auxiliary exhaust port.

11 designates the main or crank shaft connected with which in the usual manner is 65 the rod 12 of the piston 23.

13 is the intake valve crank shaft connected with which in the usual way is the rod 14 of the intake valve. 15 designates the exhaust valve crank shaft connected with 70 which in the usual manner is the rod 16 of the exhaust valve. These crank shafts are mounted in a suitable casing 17 secured below the explosion cylinder and valve chests as shown.

The valves in the present instance are 75 designed to be driven from a crank shaft geared to the main motor crank shaft at a ratio of four revolutions of the main shaft to one of the valve cam shaft. To this end 80 there is keyed on the main crank shaft 11 beyond the casing a spur gear 18 and on the shafts 13 and 15 gears 19 and 20, each of the latter being of twice the diameter of the gear 18. On an auxiliary shaft at 21 85 above and meshing with the gear 18 is a spur gear 22 of twice the diameter of the gear 18; and on said auxiliary shaft is a spur gear 23 of a diameter equal to that of the gear 18 said gear 23 being located 90 intermediate the gears 19 and 20 and adapted to engage and turn the latter in opposite directions. The motions imparted to the valve crank shafts by the revolution of the main crank shaft are consequently equal 95 to each other and as one is to four of the main crank shaft. It is obvious that in this arrangement the travel of the valves (the motion of the crank-shaft being uniform) will have greater speed when the 100 cranks are passing through the vertical arcs $a-b$ and $e-d$ and $e-f$ and $g-h$. In this way economy of motion is effected and wear on the valves is reduced. From the sequence in the cycle, the valves have their 105 slowest motion during the period of the work stroke, thereby reducing friction and wear.

At 24 is the seat of any suitable sparking plug.

The operation of the mechanism for imparting motion to the valves due to the regular travel of the crank shaft as will be understood is practically noiseless and the quick opening of the ports is a very desirable feature. It will be observed that by reason of the particular gearing and arrangement of ports that the ports are opened for work and closed both on the up and down strokes of the valves. The auxiliary exhaust port however is closed by the piston itself when the latter is up.

The construction of the two valves is such that a blast of air from any suitable source can be admitted at the top and blown out through the openings 4^b and 9^b and 5^b and 10^b respectively at the bottom as before described. The exhaust valve performs two functions or the one valve controls two exhaust openings, one at the upper end of the cylinder and one at the bottom. The bottom port allows the greater portion of the burnt charge to escape at the end of the work stroke and the upper port allows the residue to be forced out on the returning stroke of the piston.

The forms, proportions and arrangement of some of the parts can be varied without departing from the gist of the invention.

What we claim is:

1. In an explosive engine, the combination of a work cylinder having a suitable intake and a main and scavenging exhaust, two valve chests for said cylinder, a piston-like valve in each chest for controlling respectively said intake and exhausts, the valve for controlling the exhausts having a port for the main exhaust and a passage for the scavenging exhaust, a main crank, a crank shaft for each of said valves, and gearing between the main and valve crank shafts for actuating said valve crank shafts each at a ratio of one revolution to four revolutions of the main crank shaft.

2. In an explosive engine, a valve chest open at one end to the atmosphere, a hollow piston-like valve for controlling a cylinder port opening at said chest, said piston like valve also being open at one end to the atmosphere and vented at a point remote from said open end to permit a circulation of cooling air therethrough.

DAVID W. JONES.

WILLIAM J. MILLER.
